US00D615368S

(12) **United States Design Patent**
Sierra et al.

(10) **Patent No.:** **US D615,368 S**
(45) **Date of Patent:** ** *May 11, 2010

(54) **SPOON**

(75) Inventors: **Diana B. Sierra**, North Bergen, NJ (US); **Adriana Kliegman**, New York, NY (US); **Jeremy Giese**, Norwalk, CT (US)

(73) Assignee: **Playtex Products, Inc.**, Westport, CT (US)

(**) Term: **14 Years**

(21) Appl. No.: **29/314,866**

(22) Filed: **May 6, 2009**

(51) **LOC (9) Cl.** **07-03**

(52) **U.S. Cl.** **D7/653**; D7/664

(58) **Field of Classification Search** ..... D7/368, D7/395, 401.2, 642–646, 649–654, 660–669, D7/675–676, 683, 688–692, 695–696; 30/137, 30/141–143, 147–150, 322–327, 329, 340, 30/342–346; 416/70 R

(57) **CLAIM**

The ornamental design for a spoon, as shown and described.

DESCRIPTION

FIG. 1 is a perspective view of a spoon of the present disclosure;

FIG. 2 is a top view of the spoon of FIG. 1;

FIG. 3 is a bottom view of the spoon of FIG. 1;

FIG. 4 is a side elevation view of the spoon of FIG. 1; the opposite side view being a mirror image thereto;

FIG. 5 is a front view of the spoon of FIG. 1; and,

FIG. 6 is a back view of the spoon of FIG. 1.

The broken lines in the drawings illustrating environmental structure or boundaries is for illustrative purposes only and forms no part of the claimed design.

1 Claim, 4 Drawing Sheets
